UNITED STATES PATENT OFFICE

HENRY B. REYNOLDS, OF LATHROP, ALABAMA.

SAW SET.

Application filed July 1, 1924. Serial No. 723,556.

To all whom it may concern:

Be it known that I, HENRY B. REYNOLDS, a citizen of the United States, residing at Lathrop, in the county of Pickens and State of Alabama, have invented certain new and useful Improvements in Saw Sets, of which the following is a specification, reference being had to the accompanying drawings.

This invention relates to improvements in saw-sets and more particularly to a device of this character for setting the teeth of cross-cut saws.

An important object of the invention is to provide in this type of device a construction which is readily portable and which may be readily secured to any suitable convenient support, as a table, the trunk of a felled tree, or the like.

A further object of the invention is to provide a device of this character in which the construction is very simple and in which all adjustments are readily effected, so that the use of tools not readily had in lumbering camps and the like is unnecessary to replacement or adjustment of parts as, for example, removal of the anvils or the like.

A still further object of the invention is to provide a novel and improved means for maintaining the saw set in position upon a convenient support.

These and other objects I attain by the construction shown in the accompanying drawings, wherein for the purpose of illustration is shown a preferred embodiment of my invention and wherein:

Figure 1 is a perspective of a saw set constructed in accordance with my invention;

Fig. 2 is a longitudinal sectional view therethrough;

Fig. 3 is a transverse section therethrough; and

Fig. 4 is a detail perspective showing the mounting of the lower anvil member.

Referring now more particularly to the drawings, the numeral 10 indicates a base which is formed from a length of bar iron of suitable size, one end of the bar being slotted, as at 11. Adjacent the opposite end of the bar, at points spaced longitudinally of the bar, vertical threaded openings 12 are formed. In these openings are first threaded the shanks of calks 13, so that the ends of the calks project beyond the lower surface of the bar for a considerable distance. The calks are then secured against

movement by means of threaded plugs 14 having screw-driver slots so that they may be rotated. These plugs lock the calks against movement and insure a proper positioning thereof and at the same time permit mounting of the calks sufficiently loose to permit of their ready removal at any time when they should be replaced. These calks may be driven into any supporting surface, as desirable, to maintain the base in position thereagainst.

At a point spaced slightly from the furcated end of the bar 10 a socket 15 is formed receiving the shank of a lower anvil 16. This lower anvil is provided upon its side face with a projecting rib 17, which engages in a channel 18 formed in the side wall of the socket 15 to prevent rotation of the anvil. The upper surface of the bar, between this socket and the slotted end 11, is provided with a further socket 19 in which engages the lower end of a pin, the purpose of which is to prevent displacement of a spring 20.

This spring abuts one arm of a bent lever 21, which arm substantially parallels the bar 10. The other arm 22 of the lever has a reduced extension 23 fitting in the slot 11 and held in position therein by a pivot pin 24. This reduced extension has a tail portion 25 which, by its engagement with the support against which the lower surface of the bar 10 is placed, will limit the separation of the free end of the arm 21 of the lever from the bar.

This free end of the lever is provided, in alignment with the anvil 16, with a bore 26, through which is directed an upper anvil member 27 for coaction with the lower anvil 16. This anvil is provided adjacent its upper end with a notch 28. The free end of the arm 21, between the bore 26 and such end, is vertically slotted, as at 29, and has horizontal aligned bores formed in the arms thus provided, as at 30. These bores intersect the bore 26 and a bolt 31 is passed through these bores and engages in the notch 28 of the upper anvil member 27 in such manner as to support the upper surface of the anvil member above the upper surface of the lever arm 21 to afford a striking face. This bolt likewise serves the purpose of clamping the arms, formed by slotting at 29, together so that the upper anvil is firmly secured in position in the socket.

A guide 32 is provided controlling the

position of the saw with respect to the anvils 16 and 27. This guide is in the form of a sheet of metal having a central slot 33 receiving the arm 21 of the lever and the 5 base, this slot opening through the lower end of the sheet. At the sides of the slot, at the lower end thereof, the sheet is flanged, as at 34, providing bar engaging wings fitting closely against the side faces of the bar, 10 the upper ends of these wings having angular portions 35 overlying the upper surface of the bar. In the bar engaging wings are formed slots 36 extending longitudinally of the bar, and the bar has extended there- 15 through a clamping screw 37 which is directed through these slots and serves to clamp the guide in adjusted position. The length of the slot is preferably made such that excessive elevation of the free end of 20 the lever would bring the arm 21 of the lever into engagement with the upper end of the slot and thus limit movement of the lever, so that an improper swinging movement of the lever when the bar is removed 25 from its support, as during transportation from place to place, be prevented. This prevention of excessive movement is likewise necessary when the surface upon which the bar 10 is placed is relatively soft, as 30 repeated engagement of the tail piece 25 of the extension 23 against a soft surface would tend to form or gouge an opening therein permitting such excessive movement.

In the use of the device the teeth of the 35 saw are placed between the anvils and the head of the upper anvil 27 struck with a hammer to effect the setting. Prior to a setting operation the gauge is, of course, set so that the teeth will extend between the 40 anvils the proper distance. It will be obvious that when a different pitch of anvil is desired or when in use the anvils become battered or worn, it is a comparatively simple operation to remove the anvils and re- 45 place them.

It will furthermore be obvious that this construction is capable of a certain range of change and modification without materially departing from the spirit of my invention and I accordingly do not limit myself to such specific structure as hereinbefore set forth except as hereinafter claimed.

I claim:—

1. In a saw-set, a base, an anvil mounted 55 in the base, a lever pivoted at one end to the base in spaced relation to the anvil and having its free end extending over the anvil of the base, means resiliently urging the free end of the lever away from the base, an 60 anvil for coaction with the anvil of the base carried by the free end of the lever and having its upper end projected above the upper surface thereof for engagement with a hammer or the like, and a common means 65 for limiting movement of the lever under

influence of the resilient means and guiding the saw to properly position the teeth with relation to the anvil.

2. In a saw-set, a base, an anvil mounted in the base, a lever pivoted at one end to the base in spaced relation to the anvil and having its free end extending over the anvil of the base, means resiliently urging the free end of the lever away from the base, an anvil for coaction with the anvil of the base carried by the free end of the lever and having its upper end projected above the upper surface thereof for engagement with a hammer or the like, and a common means for limiting movement of the lever under influence of the resilient means and guiding the saw to properly position the teeth with relation to the anvil, comprising a member longitudinally adjustable upon the base having a slot within which the lever operates. 70 75 80

3. In a saw-set, a base, an anvil mounted in the base, a lever pivoted at one end to the base in spaced relation to the anvil and having its free end extending over the anvil of the base, means resiliently urging the free end of the lever away from the base, an anvil for coaction with the anvil of the base carried by the free end of the lever and having its upper end projected above the upper surface thereof for engagement with a hammer or the like, the free end of said lever being longitudinally slotted and having a bore aligned with the anvil of the base 90 95 in which the upper anvil is mounted and with which the slot communicates, a transverse bore formed through the lever intercepting the vertical bore at the inner end of the slot, the anvil having a notch alining with said transverse bore, and a clamping securing element extended through said transverse bore to clamp the sections of the end of the lever formed by the slot in the end of the lever and to maintain the anvil against rotation. 100 105

4. In a saw-set, a base comprising a bar slotted at one end, an anvil mounted on the base in spaced relation to such slotted end, a lever having a reduced portion pivoted in the slot of the base and having its free end extending over the anvil of the base, a spring extending between the base and lever and urging the free end of the lever away from the base, an anvil for coaction with the anvil of the base carried by the free end of the lever, and means for limiting the movement of the free end of the lever away from the base, forming a guide for the teeth of the saw to be positioned with relation to said anvils. 110 115 120

5. In a saw-set, a base comprising a bar slotted at one end, an anvil mounted on the base in spaced relation to such slotted end, a lever having a reduced portion pivoted in the slot of the base and having its free end extending over the anvil of the base, a 125

spring extending between the base and lever and urging the free end of the lever away from the base, an anvil for coaction with the anvil of the base carried by the free end of the lever, and means for limiting the movement of the free end of the lever away from the base forming a guide for the teeth of

the saw to be positioned with relation to said anvils, said means being adjustable longitudinally of the base. 10

In testimony whereof I hereunto affix my signature.

HENRY B. REYNOLDS.
